13 Claims. (Cl. 179—F71)

1

This invention relates particularly to television circuits wherein direct current reinserting circuits are utilized to restore the D. C. component of the video or image signals where the D. C. component has been removed due to amplification of the signals in amplifiers of the A. C. type. Further the invention is particularly concerned with television apparatus and circuits of a form such that the insertion of the direct current component of the signal is made in such a manner that it appears in the signal applied to the grid or input circuit of the power amplifier tube of a transmitter.

Various ways and means have already been described in the patented and published art which provide for reinserting the direct current component of a video signal at both the transmitter and at the receiver end of television systems. These D. C. reinserting circuits usually comprise a diode tube which is connected across the input circuit of some electronic discharge or relay device. Various forms of circuits to achieve these objectives have been utilized and have been found to function reasonably satisfactorily, but many difficulties have still been encountered where provisions have been made for applying signals to a grid modulated power amplifier stage where the impressed signal includes the D. C. component and the modulating signal is applied from a cathode output of a suitable vacuum tube.

In systems of all of these types, suitable amplification of the signal is frequently found to be necessary, both from the standpoint of relaying the signals by radio or cable links to remote points and from the standpoint of transmitting the signals by radio transmitters to remotely located receiving points. In this connection, frequently, difficulties have been encountered due to the fact that the bias on the modulated power amplifier stage is not maintained constant with the result that an accurate control of the amplifier tube becomes extremely difficult if not totally unobtainable in a satisfactory manner.

Accordingly, as one of the aims and objectives of the present invention, recourse is had to a system wherein the D.-C. component of the signal is inserted at the grid of a thermionic relay tube by means of the well-known diode connected in such a manner as to provide for restoration of the D.-C. video signal component. The invention is further characterized through the use of a compensating tube connected across the circuit used to supply modulating signals to the power amplifier grid. The compensating tube, so utilized, is preferably arranged so that any flow of current

2

occurring through it occurs from cathode to plate, while the current flow through the grid modulated power amplifier tube occurs from cathode to grid. In this way, the present invention prevents any current flow from the grid circuit of the power amplifier tube from passing through the load resistor of the cathode follower driver tube and thereby varying the bias established for normal operation on the power amplifier.

It may, if desired, also be considered that no change in grid bias occurs at the power amplifier grid with the compensating tube in use because should the power amplifier grid current tend to flow through the cathode output resistor of the driver tube it will be balanced out by plate current from the compensating tube tending to flow through the same resistor in the opposite direction. Regardless of the explanation, as will appear from a detailed consideration of the circuit later to be described, compensation to balance out the effect of the power amplifier grid current is provided by the compensating tube.

With the foregoing features of novelty broadly defined, it will be appreciated that the present invention has as one of its objects that of providing increased stability of operation of a power amplifier stage where the D.-C. component of the signal has been restored at the time the said signal is caused to control the amplified output from the power amplifier.

Another object of the invention is to provide ways and means to compensate for any tendency of current flow in the grid circuit of the power amplifier tube tending to vary stabilized operation of the system through our changing of the bias due to voltage drops developed in the output resistor of the driver.

A further object of the invention is to provide ways and means for relaying television signals and for transmitting said signals with increased operational efficiency.

Still other objects of the invention are those of overcoming through the use of relatively simple circuits one or more known defects of prior art systems and for establishing a relay system which is extremely efficient and stable in its operation.

Other objects and advantages of the invention will become apparent and at once appreciated from a consideration of the following specification in connection with the accompanying drawings wherein:

Fig. 1 shows one form of D.-C. insertion network in which a cathode output is used to control the signal supplied to the amplifier, and;

Fig. 2 is an improvement of the circuit arrange-

ment of Fig. 1 wherein the compensating tube is included in the complete circuit.

Referring now to the drawings for a further understanding of the invention and first to Fig. 1 thereof, an arrangement is shown whereby video signals supplied to the input terminal 11 are fed through a plurality of tubes to an output terminal 13 whereat they are applied directly to the grid and control electrode of a power amplifier stage (not shown) as is exemplified by Fig. 1. The 10 input signals which are impressed upon the terminals 11 may be considered as being video signals from which the D. C.'s component has been removed. These signals are applied to the grid or control electrode 15 of an amplifier tube 17 which may be regarded as having its cathode 19 connected to ground at 21 and its anode 23 connected to a source of positive voltage (marked +B) connected at terminal 25 with the load resistor 27 being intermediate the anode 23 and the terminal 25. Coupling of the output signal from the amplifier 17 to the control electrode 29 and the amplifier 31 is through the coupling condenser 33. The direct current reinserting circuit, which is of the general nature set forth and claimed in U. S. Patent No. 2,240,281, granted to R. C. Ballard on April 29, 1941, comprises essentially a rectifier tube 35, such as a diode, which has its cathode 37 connected to the lower end of resistor 39 by way of the condenser 41 and the anode element 43 thereof connects to ground or at least to a negative terminal point 45, as indicated. The complete diode 35 is shunted by a resistor 47.

As is well known in the television art, the D. C. potential which is a measure of the background brilliance of the television subject which is to be transmitted, appears at the cathode element 37 of the diode 35 and this voltage is connected to the grid or control electrode 29 in tube 31 by way of the resistor element 49. Where desired, a variation of the said bias, which is applied to the tube 31, may be effected in known manner by adjusting the potential of the cathode relative to the grid.

Operating voltages for the tube 31 are applied from a terminal 51 (marked also +B) from which voltages are applied to the anode 53 and the screen electrode 55. Accordingly, there appears at the output of the tube 31 across the cathode load resistor 57, a voltage which represents the signal input, conventionally shown by the curves immediately above tube 17, with the D.-C. component restored. This output voltage is then passed along the conductor 59 to the output terminal 13 for the purpose of modulating the grid of the power amplifier. By an adjustment of the bias applied at the terminal point 45, which serves as the D.-C. bias in the system, and taking into account the voltage drop occurring in this resistor 17 due to the flow of current in the cathode follower tube 31, it is apparent that various ways to adjust the normal bias applied to the grid of the power amplifier (not shown) connected to terminal 13 may be established.

In the modification of the invention shown by Fig. 2, the circuit comprises essentially the elements already described in connection with Fig. 1 and for like parts like numerals have been applied. However, for the purpose of providing compensation for any tendency of the bias on the power amplifier tube 61 to vary, recourse is had to a compensating tube 63 which is connected in the circuit in a manner later to be described. It

can be appreciated that with the D.-C. component of the modulating signal inserted at the grid 29 of the cathode follower tube 31 by means of the diode 35 due to the follower characteristics of the tube 31, the voltage, which appears in the conductor 59 across the resistor 57 connected to the cathode 56 of tube 31, is of like polarity to the signal applied to the input grid 29. The signal in conductor 59 also has the proper D.-C. component so that this proper D.-C. component will be inserted into the final transmitted or relayed signal providing no appreciable change on the bias of the power amplifier tube 61 occurs.

It is a well known fact that in transmitter operations, a tendency always exists for the power amplifier tube, when grid modulated, to draw a relatively heavy grid current, and to this extent, when signal voltages, such as those represented adjacent the conductor 59, for instance, are applied to the modulating grid 65 of the power amplifier tube which has its cathode 67 connected to ground 21, there will be a tendency for grid current to flow within the tube. This grid current flow will then flow through the cathode resistor 57 of the cathode follower stage in the absence of any compensation and, unless the current of the cathode follower is very large in comparison to the grid current of the power amplifier, a change in bias on the power amplifier tube will occur due to voltage drop in the cathode resistor 57. However, due to the fact that the power amplifier tends to draw under normal conditions an appreciable grid current, provisions are made by this invention for a compensating tube 63 to nullify the detrimental effects resulting from this condition.

It is apparent that this effect of grid current flow in the power amplifier will not be as pronounced with a low value for the cathode resistor 57 but it is extremely inefficient operation of the cathode follower stage to use a small value of load resistance. It is known that if the resistor 57 is of an appreciable value, such for instance of the order of 1,000 to 1,500 ohms (D.-C. value) and a plate current flow through tube 31 is of the order of 40 milliamperes a higher efficiency of the cathode follower stage will result than if a low output resistor is used. However, without compensation it can be seen that grid current flow from the power amplifier which is directly connected to conductor 59 will flow through the load resistor 57 and produce therein a substantial voltage drop to react at the power amplifier grid to change its bias and make the operation unsatisfactory.

To counteract the effect of this voltage variation this invention provides a compensating tube 63 which has its grid or control electrode 71 connected by way of conductor 73 and the resistor 75, with capacity 77 connected to ground, as shown, to the point 81 whereat the corrected D.-C. voltage appears, so that in accordance with the potential appearing upon the grid 71 of the compensating tube 63 relative to the cathode 69 thereof, a tendency exists for current to flow within the tube 63 in a direction between the tube cathode and the plate or anode 79, which latter electrode connects at terminal point 81 to a source of positive operating potential. The bias on the tube 63 will automatically be adjusted in accordance with the time constant of the circuit including resistor 75 and capacity 77. Under these conditions, it will be appreciated that the use of the compensating tube 63 is such that it prevents any grid current tending to flow through the power amplifier from

flowing through the cathode load resistor 57, whereby a change in bias on power amplifier grid 65 would be occasioned so the current flow in the tube 63 thus can be made to balance and compensate for the grid current flow in the power amplifier tube 61 whereby stabilized modulating conditions are achieved.

If the mutual conductance of tube 63 is correctly set the compensation provided is such that correct D. C. insertion is maintained at the power amplifier tube. With greater mutual conductance in tube 63 it is possible to create the effects of over D. C. insertion at the power amplifier. Such over D. C. insertion may be utilized to overcome the detrimental effects of cathode bias on the cathode of the power amplifier tube, where desired.

Various modifications of the system herein set forth and claimed may of course be relied upon and is believed that any and all of these modifications may readily be used so long as they fall fairly within the spirit and scope of what is hereinafter claimed.

We claim:

1. In a video circuit wherein video signals are to be transferred from a signal input an output load circuit which includes a power amplifier tube which tends to draw grid current when signal modulated the combination which comprises a coupling tube connected intermediate the point of video signal input and the grid input circuit of the power amplifier tube, a D. C. re-inserting unit connected to respond to the input video signals and to supply therefrom the D. C. component at the input of the coupling tube, a cathode follower connection from the coupling tube cathode to the grid input of the power amplifier tube to supply thereto output signals from the coupling tube in which the D. C. component has been restored and a compensating and voltage regulator tube connected in parallel with the input circuit of the power amplifier tube to maintain a predetermined bias upon the power amplifier.

2. In a television circuit wherein video signals are to be transferred from a signal input point to a load circuit including a power amplifier tube which tends to draw grid current when signal modulated the combination which comprises a coupling tube connected intermediate the point of video signal input and the grid input circuit of the power amplifier tube, means for re-inserting the D. C. component of the impressed video signals at the input of the coupling tube, a cathode resistor connected to the coupling tube cathode across which output signals from the coupling tube may be derived, a direct connection from a predetermined point on the cathode resistor to the grid input of the power amplifier tube to supply thereto output signals from the coupling tube in which the D. C. component has been restored and a compensating thermionic tube connected in parallel with the cathode resistor to compensate for any tendency of grid current flow in the power amplifier tube tending to produce a voltage drop in the said cathode resistor which would alter the bias of the power amplifier tube.

3. The circuit claimed in claim 1 comprising in addition, means to control the current flow through the voltage regulator tube in accordance with the control of the re-inserted D. C. signal component.

4. In a television circuit wherein video signals are to be transferred from an input to a load

70
75

circuit which includes a power amplifier tube which tends to draw grid current when signal modulated the combination which comprises a coupling tube connected intermediate the point of video signal input and the grid input circuit of the power amplifier tube, means for re-inserting the D. C. component of the impressed video signals at the input of the coupling tube, a cathode resistor connected to the coupling tube cathode across which output signals from the coupling tube may be derived, a direct connection from a predetermined point on the cathode resistor to the grid input of the power amplifier tube to supply thereto output signals from the coupling tube in which the D. C. component has been restored, a compensating thermionic tube connected in parallel with the cathode resistor to compensate for any tendency of grid current flow in the power amplifier tube tending to produce a voltage drop in the said cathode resistor which would alter the bias of the power amplifier, and means to control the current flowing in the compensating tube in accordance with the re-inserted D. C. component of the impressed signal.

5. The combination claimed in claim 4 comprising, in addition, a time constant circuit for maintaining the effect of the re-inserted D. C. component controlling the current flow through the compensating tube for predetermined time periods.

6. In a television circuit wherein video signals are to be transferred from an input circuit to a load circuit including a power amplifier tube which tends to draw grid current when signal modulated the combination which comprises a coupling tube connected intermediate the point of video signal input and the grid input circuit of the power amplifier tube, means for re-inserting the D. C. component of the impressed video signals at the input of the coupling tube, a cathode resistor connected to the cathode of the coupling tube, a direct connection from a predetermined point on the cathode resistor to the grid input of the power amplifier tube to supply thereto output signals from the coupling tube which are developed across the cathode resistor and in which the D. C. component has been restored, a voltage regulator unit connected in parallel with the signal supply to the power amplifier tube grid input to maintain the grid circuit impedance of the power amplifier tube substantially constant.

7. In a television circuit wherein video signals are to be transferred from an input circuit to a load circuit including a power amplifier tube which tends to draw grid current when signal modulated the combination which comprises a coupling tube having an input circuit connected to receive the video signal input and a cathode follower output circuit directly connected to supply output signals to the grid input circuit of the power amplifier tube, means for re-inserting the D. C. component of the impressed video signals in the input of the coupling tube so that the output signal includes the D. C. component, and a voltage regulator tube connected in parallel with the cathode follower output to maintain the grid circuit impedance of the power amplifier tube substantially constant.

8. The circuit claimed in claim 7 comprising, in addition, means to control the current flow in the voltage regulator tube in proportion to the D. C. component signal restored and supplied to the coupling tube.

9. The circuit claimed in claim 7 comprising, in

addition, means to control the current flow through the voltage regulator tube from the restored D. C. component signal and a time constant circuit to maintain the control voltage effective in the voltage regulator tube for predetermined time periods.

10. In a television circuit wherein video signals are to be transferred from an input to a load circuit including a power amplifier tube which tends to draw grid current when signal modulated the combination which comprises a coupling tube connected intermediate the point of video signal input and the grid input circuit of the power amplifier tube, signal rectifier means for reinserting the D. C. component of the impressed video signals at the input of the coupling tube, a cathode resistor connected to the coupling tube cathode so that output signals may be derived therefrom in which the direct current component has been added, a direct connection from a predetermined point on the cathode resistor to the grid input of the power amplifier tube to supply thereto the output signals from the coupling tube, a compensating tube connected in parallel with the signal supply to the power amplifier tube grid input to maintain the grid circuit impedance of the power amplifier tube substantially constant, and a connection to supply a signal representative of the D. C. component of the input signal to the compensating tube to control the current flow therethrough.

11. In a television circuit wherein video signals in which the D.-C. component has been restored are to be transferred to a load circuit including a power amplifier tube which tends to draw grid current when signal modulated the combination which comprises a coupling tube connected intermediate a point of video signal input and the

grid input circuit of the power amplifier tube for transferring the video signals with the re-inserted D.-C. component from the signal input circuit to the power amplifier tube, a cathode resistor connected to the coupling tube cathode across which resistor output signals from the coupling tube are derived, a galvanic connection from a selected point on the said cathode resistor to the grid input of the power amplifier tube to supply output signals in which the D.-C. component has been restored from the coupling tube to the power amplifier tube, a voltage regulator unit connected in parallel with the signal supply to the power amplifier tube grid input to maintain the grid circuit impedance of the power amplifier tube substantially constant.

12. The circuit claimed in claim 11 comprising, in addition, means to control the current flow in the voltage regulator tube from the restored D.-C. component signal restored and supplied to the coupling tube.

13. The circuit claimed in claim 11 comprising, in addition, means to control the current flow through the voltage regulator tube from the restored D.-C. component signal and a time constant circuit to maintain the control voltage effective in the voltage regulator tube for predetermined time periods.
